UNITED STATES PATENT OFFICE.

BERNARD HAUSMANN, OF NEW YORK, N. Y.

WINDOW.

1,272,039.

Specification of Letters Patent.

Patented July 9, 1918.

Application filed July 25, 1914. Serial No. 853,000.

To all whom it may concern:

Be it known that I, BERNARD HAUSMANN, a citizen of the United States, and a resident of the borough of Manhattan, city, county, 5 and State of New York, have invented certain new and useful Improvements in Windows, of which the following is a specification, accompanied by drawings.

This invention relates to windows, but 10 more especially to a window of the double hung counterweighted or counterbalanced type, both sashes of which slide vertically in the usual manner and may be swung inwardly and retained in such position at any 15 desired horizontal angle. The particular object of this invention is to provide means of ventilation without creating draft and to regulate such ventilation as desired and further, to provide the means of washing 20 both sides of the glass of a window from the inside of the room with a secure manner of construction and operation.

In a window of this type the lower sash can be swung inwardly at any given point 25 of the height of the window frame and I have found it highly desirable to provide means for preventing the upper sash from being swung inwardly until it is lowered to substantially its lowermost position at 30 the sill.

By raising the top part of the lower sash above the head of the window frame and thus providing space for clearance, the upper sash may be swung inwardly when 35 lowered to the sill, and freely handled to facilitate the cleaning of the glass at both sides. Both sashes are restored to their normal vertical position in the window-frame by simply reversing the operations as de- 40 scribed. I am furthermore enabled to pro- vide a simple and efficient system of weather stripping for both sashes, which is a fac- tor of the utmost importance in such win- dows.

45 My construction is to be differentiated from the so-called "split sash," which com- prises three parts, that is, the sash proper, and the strips at each side which have slid- ing movement in the window frame. Such 50 "split sashes" have inherent objections which are difficult, if not impossible to overcome, and are a constant source of trouble. The strips being necessarily narrow, are apt to warp and prevent the sash from ready dis- 55 engagement when it is desired to swing the sash inwardly or to reengage again with

the sash when to be swung back into its ver- tical position. They prevent a tight joint to keep out wind and weather, impair the free travel of the entire sash in the window 60 frame and obstruct the free operation of the sash. Furthermore, the split sash, consisting of jointed members affords greater opportunities than the normal sash for the weather, drafts and dust to enter, and it 65 therefore materially impairs the window in its more essential requirements of protec- tion against the elements.

The objects of my present invention are to improve upon the construction of win- 70 dows of the type herein specified, and obviate the difficulties heretofore encountered in the satisfactory construction and operation of such windows. I am enabled to reduce the 75 number of parts necessary for efficient op- eration of the sashes to a minimum, thus reducing the cost of the construction, and I do not alter the general appearance of an ordinary double hung window, yet at the 80 same time I am enabled to make a thor- 85oughly weather-tight window without con- structional difficulties.

In my window, the sash proper is directly 85 and pivotally connected by arms to upper slides, which travel in grooves in the jamb of the window frame, and these slides are connected to the sash chains. Lower inde- 90 pendent slides are also pivotally connected to the lower end of the sash. The arms are adapted to lie in recesses formed in the jamb 95 of the window frame and in the sides of the sash, so that said arms are hidden from view when the sash is in normal closed po- 95 sition, and a better weather tight joint may be formed.

I have found that the sash is apt to rock 100 sideways on its lower pivots when swung in- wardly, due to the independent movement of the slides at each side and other causes, and one of my improvements consists in pro- 105 viding locking means for the slides for pre- venting this rocking action and thereby stabilizing the sash when swung in.

These locking devices are preferably 110 automatic in action, and are preferably ap- plied to the pivotal connections between the upper ends of the arms and the slides. These locking devices are also preferably so constructed that the lock is not brought into operation until the sash is swung in- 115 wardly beyond a predetermined angle, so that the sash may be swung inwardly at a

given angle and may still slide up and down, but beyond this given angle, the slides become locked in the grooves in the jamb of the window frame. By this means the rocking 5 of the sash when swung inwardly is avoided, and a firm, efficient, and practical construction is provided, safe in operation.

Another improvement consists in providing holding means, preferably in conjunction 10 with the pivotal connections of the arms with the sash, and preferably automatic in action, for holding the sash at any desired angle, when swung inwardly. This has been found to be a very desirable feature, because 15 the sash may thus be swung inwardly and made to stay in any desired position against wind pressure for purposes of regulating ventilation or to afford the means of washing both sides of the glass from the interior 20 of the room.

The invention consists of means for carrying out all the above objects and the invention is illustrated in the best form known to me in the accompanying drawings, in 25 which—

Figure 1 is an elevation partly in vertical section of a window constructed in accordance with this invention;

Fig. 2 is an enlarged detail side view 30 partly broken away of the pivotal locking connection between one of the arms and the sash;

Fig. 3 is an enlarged detail edge view of Fig. 2;

Fig. 4 is a detail face view partly in section of one of the locking members shown in Fig. 2;

Fig. 5 is a longitudinal sectional view 40 partly broken away of Fig. 2 taken on the line 5—5 looking in the direction of the arrows;

Fig. 6 is an enlarged detail perspective view of the pivotal connections for the lower end of the upper sash;

Fig. 7 is an enlarged detail perspective view partly in section of the pivotal connections for the lower end of the lower sash;

Fig. 8 is an enlarged detail perspective view partly in section and partly broken 50 away illustrating the construction of the window;

Fig. 9 is a detail horizontal sectional view taken through one side of the window;

Fig. 10 is an enlarged detail side view 55 partly broken away of the pivotal locking connection between the upper end of one of the arms and the slide;

Fig. 11 is a detail horizontal sectional view taken through the pivot of Fig. 10;

Fig. 12 is a detail vertical sectional view 60 taken through the pivot of Fig. 10; and

Fig. 13 is a detail perspective view of the pivotal connection between the upper end of one of the arms and the slide, and the 65 chain connection.

Referring to the drawings, A represents the jamb at one side of the window frame, the other side not being shown, for convenience of illustration, B represents the top of the window frame or lintel, C represents 70 the window-sill and D and E indicate the sash weights in the usual boxes, it being understood that the window frame construction shown and described is substantially like the construction for any ordinary window of the double hung, counterweighted or counterbalanced type, with the differences hereinafter pointed out, which pertain to my invention.

Both the lower sash F and the upper sash 80 G are adapted to slide vertically in the usual manner and may be swung inwardly and retained in such position at any desired horizontal angle, by means of the operative parts connected thereto. The lower sash F 85 may slide throughout the height of the window and may be swung inwardly at any desired vertical position, but in accordance with my invention, the upper sash G which is shown in dotted lines in Fig. 1 is not 90 adapted to be swung inwardly when in its uppermost or raised position, and in the operation of the window, the upper sash is adapted to be lowered substantially to its lowermost position before it can be swung 95 inwardly. Ordinarily the lower sash F would be swung inwardly and may then be partly raised above the head of the window frame in such position while at an angle and then the upper sash G can be lowered 100 and swung inwardly. In this way interference between the sashes, for cleaning and ventilating purposes, is obviated.

Both sashes as shown move in recesses in the jamb of the window frame, the recess for 105 the lower sash F being formed by the rabbet H and the recess for the upper sash being formed by the rabbet J, it being understood that the construction of both jambs of the window frame is the same. A strip K preferably of heavy stock and preferably in the form of an angle, is provided in the recess or rabbet J for the upper sash G and said sash is provided with a longitudinal groove L into 110 which the weather strip K extends. This weather strip K extends vertically throughout only the upper half of the window frame and terminates at the point a or slightly below, as indicated in Fig. 1, so that when the upper sash is in its normal raised position, 115 it cannot be swung inwardly, but said sash must be lowered to clear the strip K, in order to permit the sash to be swung inwardly. The combination of the rabbet J and the outwardly projecting strip K coöperating with 120 the groove L in the upper sash G forms an efficient weather-tight joint and acts at the same time as a means of holding the sash against wind-pressure in its normal vertical position in like manner as the usual part- 125 130

ing bead serves this same purpose in an ordinary window.

The strip K, made of heavy stock, serves two distinct purposes, one as important as the other, in that it takes the place of the usual parting bead, serving as a means to hold the sash against wind pressure in its normal position, and also serves as an effective weather strip as specified.

10 A weather strip O preferably of metal and preferably in the form of a channel is provided in the rabbet H for the lower sash F and said channel, as shown, faces inwardly and coöperates with a similar channelled metallic weather strip P secured to the lower sash F. The weather strip O preferably extends substantially throughout the height of the window and in connection with the rabbet H and the coöperating channelled strip P on the sash, forms an efficient weather-tight joint, by interfitting with the channels O.

The jambs of the window frame, as shown, are provided with grooves in the pulley 25 stiles back of the edges of the sashes and these grooves may be in the form of metallic tracks Q, preferably having the inwardly extending retaining members or flanges b, as shown in detail in Figs. 10 and 11. Mov- 30 able upper slides R preferably in the form of blocks or strips of metal are retained in said grooves or tracks Q and said upper slides are connected with the sash weights D and E as by means of the usual sash cords 35 or chains c.

Arms S are pivoted to the slides at one end and pivoted to the sash at the other end, the pivotal connections of these arms S for both the upper and lower sashes being sub- 40 stantially the same, so that the connections of only one set of arms need be described, and these arms S afford means for raising and lowering the sash vertically in its regular frame-guides and for swinging the sash 45 inwardly and holding it in such position.

The bottom of the lower sash F is provided with members d at each side having a pivotal connection with lower independent slides e shown in detail in Fig. 7 which also 50 travel vertically in the grooves f in the jamb of the window frame. As shown, in this instance, the slide e is provided with the stud or pivot pin g engaging the aperture h in the member d, thereby forming a pivotal 55 connection. The lower slides e slide independently of the upper slides, it being understood that the construction at both sides of the window is the same. The edge at the bottom of the upper sash G is also 60 provided with the members j, in this instance provided with the pins k engaging apertures o respectively in the lower slides p sliding vertically in the grooves or tracks Q, the detail of this pivotal connection being 65 shown in Fig. 6. Suitable means are pro-

vided for maintaining the lower sash F in closed position and as a convenient construction I have shown a spring latch q secured to the sash, and having a tongue r which engages the groove f in the window frame. 70 The tongue r is retracted from engagement with the groove f when it is desired to swing the lower sash F inwardly.

Suitable means are provided for holding or latching the sashes at any desired angle 75 when swung inwardly and I prefer an automatic lock arranged in connection with the pivotal connections of the arms S to the sashes. The details of this locking or latching device are shown in Figs. 2, 3, 4 and 5, in 80 which s is a socket piece adapted to be set into the side of the sash and provided with a central bolt t over which is placed a coiled spring u adapted to be compressed between the bottom of the socket piece s and a holding member v, held in the socket piece and preferably provided as shown with the radial teeth w. Another holding member or clutch member x is held beneath the head y of the bolt and is provided on its face with 90 teeth or grooves coöperating with the teeth w of the member v. The member x is adapted to be rotated on the bolt and the arm S is adapted to be rigidly connected to the member x as by means of the pins z. The 95 screw 5 passing through the arm S and screwed into an interiorly screw threaded socket 6, in the bolt t, holds the arm S and locking members together, so that as the sash is moved inwardly and outwardly, the 100 toothed holding member s turns on the locking member v and the coöperating teeth hold or latch the pivotal connection in any desired position.

In order to prevent the rocking of the 105 sash when swung inwardly, due to the relative movement between the upper and lower slides and other causes, I provide means in connection with the pivotal connection of the arms S with the upper slides, for locking 110 the upper slides to the grooves or tracks and I prefer that this locking of the slides should not be brought into operation until the sash has been swung inwardly beyond a certain predetermined angle, because it is desirable 115 that the sash should be free to slide vertically after it has been swung inwardly to a certain degree.

This automatic locking arrangement for the upper slides is illustrated in detail in 120 Figs. 10, 11, 12 and 13 and as shown each upper slide is provided with a stud or pin 7 preferably having a squared shank 8, a round throat and an oval beveled head 10. A plate 11 is loosely arranged on the squared 125 shank 8 and is provided with a suitable hook 12 or other engaging means for the pulley chain c. The arm S is provided with a round aperture 13 in its end coöperating with a round throat 9 and the edge of the aperture 13 is 130

- beveled at 14 preferably at a slightly different angle from the bevel of the head 10, so that as the sash is swung inwardly and the arms S rotate on the pivots 9, the plates 11 5 are squeezed or forced against the tracks Q and lock the slides. There is, however, sufficient play in the pivotal connections of the arms S as described, to permit the sash to be swung inwardly to a given angle of about 10 15 degrees more or less before the locking of the slides takes place and beyond this angle the slides become more firmly locked in position, so that rocking of the sash cannot take place. The rocking is further prevented by 15 the locking connections of the arms S with the sash and a very firm and rigid construction is provided, which has been found to operate efficiently and well in actual practice.
- I claim and desire to obtain by Letters 20 Patent the following:
1. A window of the double hung counterweighted or counterbalanced type, having a sash which slides vertically in the usual manner and may be swung inwardly and retained 25 in such position at any desired horizontal angle, grooves in the jamb of the window frame, movable slides retained in said grooves, said slides connecting with the sash chains, arms pivoted at one end to said slides, said arms being pivoted at the other ends to the sash, and holding devices for the pivotal connections of the arms and the sash, whereby the sash may be locked at any desired angle.
  - 30 2. A window of the double hung counterweighted or counterbalanced type, having a sash which slides vertically in the usual manner and may be swung inwardly, grooves in the jamb of the window frame, movable slides retained in said grooves, said slides connecting with the sash chains, arms pivoted at one end to said slides, said arms being pivoted at the other ends to the sash and automatic holding devices for the pivotal connections at both ends of the arms.

being pivoted at the other ends to the sash, and locking devices for the pivotal connection of the arms and the slides, whereby the sash may be locked at any desired height in open position.

3. A window of the double hung counterweighted or counterbalanced type, having a sash which slides vertically in the usual manner and may be swung inwardly and retained in such position at any desired horizontal angle, grooves in the jamb of the window frame, movable slides retained in said grooves, said slides connecting with the sash chains, arms pivoted at one end to said slides, said arms being pivoted at the other ends to the sash, and holding devices for the pivotal connections of the arms and the sash, whereby the sash may be held at any desired angle, and locking devices for the pivotal connections of the arms and the slides, whereby the sash may be locked at any desired height in open position.

4. A window of the double hung counterweighted or counterbalanced type, having a sash which slides vertically in the usual manner and may be swung inwardly and retained in such position at any desired horizontal angle, grooves in the jamb of the window frame, movable slides retained in said grooves, said slides connecting with the sash chains, arms pivoted at one end to said slides, said arms being pivoted at the other ends to the sash and automatic holding devices for the pivotal connections at both ends of the arms.

In testimony whereof I have signed this specification in the presence of two subscribing witnesses.

BERNARD HAUSMANN.
